CONCENTRATING MACHINE

Clayson R. Hammond, Salem, Oreg., assignor of
fifty-five per cent to John L. Lynch, Salem,
Oreg.

Application November 20, 1940, Serial No. 366,499

6 Claims. (Cl. 209—437)

This invention relates to improvements in concentrating machines and is particularly adapted for recovering materials approaching and including the specific gravity of the heavier metals.

The primary object of my invention is to provide a recovery system that will intermittently sluice the materials being processed and settle and trap the heavier materials alternately with the sluicing. In my new and improved recovery system the sluicing operations move the material through the recovery units, the sluicing being momentarily halted, permitting the heavier materials to concentrate underneath the movement of lighter materials on the recovery units. The frequency of change from sluicing to recovery may be governed to correspond to the materials being processed, by suitable mechanism provided in the machine for controlling the operation of the recovery units.

A further object of my invention is the provision of a new and novel oscillating movement to be imparted to the screening system for the screening of the materials to be delivered to the recovery units.

A still further object of my invention is the provision of means for controlling the nature of oscillations imparted to the screening system and for controlling the direction of travel of materials over this screening system to meet different working conditions.

These and other incidental objects will be apparent in the drawings, specification and claims.

Referring to the drawings:

Figure 1 is a side assembled view, parts broken away for convenience of illustration, of my new and improved concentrator.

Figure 2 is a sectional detail view of the method of fabricating the framework of the machine.

Figure 3 is an end sectional view of the recovery units, taken on line 3—3 of Figure 1, looking in the direction indicated and showing diagrammatically the flexible concentrator.

Figure 4 is a bottom plan partly in section of the concentrator, illustrating the mechanism for operating the recovery units.

Figure 5 is a fragmentary side elevation of Figure 4 partly in section, taken on line 5—5, looking in the direction indicated, illustrating the relation of the assembled parts.

Figure 6 is a fragmentary diagrammatical sectional end view of the recovery unit.

Figure 7 is a fragmentary sectional view, taken on line 7—7 of Figure 6, looking in the direction indicated. This is the position of the recovery units during the sluicing operation.

Figure 8 is a sectional view, taken on line 8—8 of Figure 6, of the recovery units in a settling and recovery position.

In the drawings:

The concentrator consists of a sub-base 1 having upwardly extending standards 2, upon which is mounted a U-shaped frame 3. The standards 2 are preferably made from I-beams having the frame 3 resting thereon and being clamped thereto by the clamping bands 4, which encircle the frame 3 and are securely clamped in place by the fastening bolts 5. The reason for adopting this system of securing the frame structure together is to prevent breakage of the frame connections due to vibrations. By using the method shown, the joints can be tightened up periodically maintaining a rigid frame construction. The screening unit is indicated by the numeral 6 and the system consists of an upper unit 7 and a lower unit 8. The assembly is supported by the links 9, having their upper ends looped over the stub shafts 10. Shafts 10 are securely fastened to the framework 11 of the concentrator. The lower ends of the links are pivotally mounted or looped over the stub shafts 12, which are secured to the upper unit 7 of the screen unit 6. The stub shafts 10 and 12 have loose bearings 13 therearound for directly contacting the link. These bearings are readily replaced when they become worn.

There are two pairs of links 9, the forward links 14 are indicated as having a less angle or incline than the rear supporting links 15, the reason for this is to provide a special upward movement of the screen assembly for progressing the materials therethrough. The lower unit 8 of the screen assembly is supported by the bolts 16 which are hooked into the frame of the units 7 at 17 at their upper ends, and pass through the bosses 18 of the lower unit 8, and are held in place by the adjusting nuts 19 at their lower ends.

I impart an oscillating movement to the screening unit in a new and novel manner, which I will now describe. Upwardly extending brackets 20 are mounted on the frame 3 by the clamps 21. Bearings are mounted upon these brackets and have a cross shaft 23 journaled therein. An eccentric 24 is fixedly secured to this shaft, and has thereabout an eccentric band 25, this band having a suitable anti-friction bearing therein. Pivotally connected to the eccentric band is a connecting rod 26 which extends toward the forward end of the machine and passes through a yoke 27 and is fastened thereto by locking nuts 28. Flexible shock absorbers 29 are interposed

between the yoke and locking nuts. The yoke 27 is loosely mounted on the upper ends of the side bars 30 upon the pin 31. The lower ends of the side bars 30 are pivotally mounted at 32 on the base 1.

Levers 33 are held at a predetermined location relative to the side bars 30, by the adjustable hangers 34. The lower end of the hangers are pivotally journaled to the lever 33 at 35. The upper end of the hanger 34 is adjustably positioned on the stub pin 36, which is fixedly secured to the side bars 30. The pivot point 35 of the lever 33 bears against the side bar 30 at 37 and provides a fulcrum point for the lever 33. The lower end of the lever is pivotally connected to the connecting link 38 at 39. The opposite end of the link 38 is adjustably mounted at 40 to the frame of the machine by the locking nut 40A. A spring 41 is interposed between the frame and the collar 42 of the link 38 for absorbing oscillating shocks. Discs 43 are pivotally mounted on the upper portion of the screening unit 7 at 44. Upon each of these discs is located the cam 45. These cams are mounted within housings 45A, which have adjusting means, as nuts 45B. The discs are positioned in any desired position about their holding pins 43, and held by the locking pins 46, which are tapped into the upper unit 7.

In operation the eccentric mechanism mounted on the shaft 23 oscillates the yoke 27, pivoting the side arms about the pivot point 32, at the same time forcing the levers 33 towards the cams 45 in the following manner: As the side bars 30 are pulled to the left they force the fulcrum points 35 of the levers 33 to the left, pivoting these levers about the pivot 39 of the links 38. This forces the cam surfaces 33A against the cam 45, swinging the screening unit on its hanger links 14 and 15, providing a rising and a lowering oscillation on the return of the levers 33. The fulcrum point 37 is raised or lowered by the hangers 34 for changing the length of oscillation imparted to the screening unit by changing the distance between the fulcrum point 37 and the cam 45. When the position of the levers 33 is changed by hangers 34, the cam contact surface 33A was changed relative to the cam 45. It is desirable to keep the thrust of cam contact surface 33A approximately in a direct line with cam 45 and disc center 44, the means of adjustment having been described above.

I will now describe the main object of my invention, namely, the system of recovering the concentrates. Referring to Figure 8, I have shown four concentrating or recovery units 61, 62, 63, and 64. These concentrating units are mounted upon a supporting shaft 65 running longitudinally of the machine, this shaft is supported upon cross shafts or spacers 66, cross shafts 66 are rigidly mounted to the frame of the machine. The longitudinally supporting shaft 65 is securely clamped to the cross shafts 66 by suitable U-bolts 66A, of well known construction. Extending transversely of the machine are channel tracks 68, 69, 70 and 71, these tracks are mounted upon the upright supports 72, which are clamped to the longitudinally supporting shafts 65 at 73.

The recovery units are made up in the following manner: They have movable side frames 74, which are mounted upon the channel tracks 68, 69, 70 and 71 by having wheels 76 journaled to the stub shafts 75, said stub shafts are fixedly secured to the ends of the side frames 74. Extending longitudinally between the recovery units are rigid frames 77, resting upon channel sup-

ports 78, supports 78 being in turn supported by the uprights 72 and uprights 79. Clamped between the frame 77 and the retaining strips 80 is pleated flexible material 81, which extend across from the frame 77 to the outside frames 74, where they are clamped in between the retaining strips 82 and the frames 74.

It will be noted by referring to the respective drawings, that while one of the recovery units is stretched more or less taut, the other recovery unit sags considerably lower and the pleats are in open condition, the reason for this will be later described. The frames 74 are held apart by connecting links 83 which are connected to the shafts 75, holding the side frames 74 at a predetermined distance apart. Running centrally and longitudinally of the recovery units 61 and 62 is operating shaft 84, journaled in uprights 85, said uprights are mounted on the channel tracks 68 and 69. Cranks 86 and 87 extend downwardly from the operating shaft 84 and have connected thereto the tension springs 88. The opposite ends of the tension springs are connected to the stub shaft 75 of the side frames 74. The operating shaft 84 operates the recovery units 61 and 62, while an additional operating shaft 90 operates the units 63 and 64. The crank arms 92 are fixed to the shaft 90 and extend downwardly having their outer ends connected to the tension springs 93. The opposite ends of the springs 93 are connected to the stub shafts 75. The cranks 86 and 92 are operated in the following manner: A crank arm 86A is oppositely disposed from the crank 86 and lines up opposite to the crank 92, both being connected together by the wrist pin 92A of the connecting rod 94 and oscillated thereby.

When the connecting rod 94 is operated in one direction, the cranks 92 position the recovery units 63 and 74 toward one side of the machine, while the cranks 86 and 87 position the recovery units 61 and 62 on the opposite side of the machine, this being done to balance the mechanism in its operation. The connecting rod 94 is operated by the bell crank 95, which in turn is pivotally mounted at 96 and is oscillated by the connecting rod 97, which terminates on the crank pin 98 of the pulley 99. The pulley 99 is carried by a suitable bearing pedestal 100 and is driven by a belt 101 from the pulley 102, the pulley 102 is keyed to the shaft 23. The shaft 23 receives its power through a pulley 103A driven by the belt 103 and counter drive mechanism 104, which in turn is driven from any suitable power means.

When the materials have been delivered from the launders 108 and 109 to the recovery units 61, 62, 63 and 64, best shown in Figures 10, 11 and 12, the following action takes place, the flexible pleated recovery unit 81 on our right, indicated by the numeral 105, is stretched almost taut throughout its length. In this position the materials sluice rapidly over its longitudinal surface with the pleats 81A more or less acting as shallow riffles. To our left the flexible pleated recovery unit indicated by numeral 106, is in its relaxed or flexed position, while in this position the flow of material is momentarily slackened allowing the concentrates to settle between the pleats as indicated at 107. When the operating shafts 84 and 90 are oscillated by the connecting rod 94, through the drive mechanism heretofore described, the relation of the recovery units will be changed. The units on our left, Figures 10, 11 and 12, indicated by numeral 106, will assume the position

shown by unit 105 and unit 105 will appear as the unit 106 on the left, therefore, the material in the unit 106 will speed up the sluicing, the pleats or pockets 107 will close, forcing out the lighter materials from the concentrates into the sluice to be carried away while the pleats in unit 105 will open to the position shown by Figure 12, slackening the sluicing and concentrating the heavier materials upon the pleats 107. This completes the cycle of operation, consisting of screening and concentrating the materials being processed.

I do not wish to be limited to the particular mechanical construction shown and described in the drawings, as other mechanical equivalents may be used still coming within the scope of the claims to follow.

What I claim is:

1. A material concentrator comprising a flexible member formed with a plurality of transversely disposed V-shaped pocket forming folds, one wall of each fold being lowermost and having a substantial portion thereof extending from the forward edge of the upper wall, the extending portion of said lower wall overlying the upper wall of an adjacent fold, and means for laterally flexing said member to thereby open and contract said folds.

2. A material concentrator comprising a frame, a flexible member in said frame, means securing the opposite longitudinal edges of said member to said frame, means secured to the opposite longitudinal edges of said member and extending lengthwise thereof for alternately flexing and tightening said member, said member comprising a flexible element formed with a plurality of transversely disposed folds constituting pockets, one wall of each fold being lowermost and having a substantial portion thereof extending from the forward edge of the upper wall, the extending portion of said lower wall overlying the upper wall of an adjacent fold.

3. In a material concentrating device, a concentrating means comprising a stationary frame, a flexible member fixed in the longitudinal center thereof to said frame, said flexible member formed with transversely disposed folds constituting pockets having their open sides opposing the flow of material over said member, and means engaging the opposite longitudinal edges of said member for shifting one portion of said member laterally of the length thereof to a substantially taut material concentrating condition while simultaneously shifting the adjacent portion of said member in the same direction to a loose material receiving condition.

4. In a material concentrating device, a concentrating means comprising a stationary frame,

a flexible member fixed at the opposite longitudinal edges thereof to said frame, said member having a plurality of pairs of V-shaped pockets formed therein, a wall of one pocket overlapping a wall of an adjacent pocket and said pockets being disposed in opposed relation to the flow of the material, and laterally movable means fixed to said member on the opposite longitudinal edges thereof pulling one portion of said member to thereby compress the pockets on one side of the center thereof while simultaneously relaxing the opposite portion of said member to thereby open the pockets on the other side of the center thereof.

5. In a concentrating device, a stationary concentrator supporting frame, a flexible member fixed in substantially the longitudinal center thereof to said concentrator frame, a plurality of transversely disposed parallel pockets formed in said flexible member, concentrator frame bars fixed to said flexible member on the opposite longitudinal edges thereof, and means connected with said frame bars for transversely flexing said flexible member whereby to constrict certain of said pockets and simultaneously open certain others of said pockets, said pockets being disposed in opposed relation to the flow of material over said flexible member, and said pockets being so constructed that one wall of a pocket overlaps an adjacent wall of an adjacent pocket and all of the walls of the pockets will be in substantially parallelism when in constricted or closed position.

6. In a concentrating device, a stationary concentrator supporting frame, a flexible member fixed in substantially the longitudinal center thereof to said concentrator frame, a plurality of transversely disposed parallel pockets formed in said flexible member, concentrator frame bars fixed to said flexible member on the opposite longitudinal edges thereof, said supporting frame including a pair of transversely disposed guide members fixed to said first frame and disposed adjacent the opposite ends of said flexible member, rollers carried by said frame bars engaging said guide members, means disposed centrally of said flexible member for transversely reciprocating said frame bars to thereby constrict certain of said pockets and simultaneously open the remaining pockets, said pockets being disposed in opposed relation to the flow of material over said flexible member, and said pockets being so constructed that one wall of a pocket overlaps an adjacent wall of an adjacent pocket and all of the walls of the pockets will be in substantially parallelism when in constricted or closed position.

CLAYSON R. HAMMOND.
